PROCESS OF BLEACHING DETERGENT SALTS

Irving J. Krems, Vienna, Austria, and Frederick William Gray, Belleville, N.J., assignors to Colgate-Palmolive Company, New York, N.Y., a corporation of Delaware

No Drawing. Filed June 4, 1958, Ser. No. 739,666

3 Claims. (Cl. 260—505)

The present invention relates to ozone-bleaching of normally solid water-soluble higher alkylbenzenesulfonate detergents which contain oxidizable color bodies.

Higher alkylbenzenesulfonate detergents are frequently somewhat discolored by the presence therein of color bodies subject to oxidation and decoloration by gaseous ozone. However, as the sulfonate is normally a solid material, it is difficult to assure efficient and complete contact of the gaseous ozone with the color bodies which are dispersed throughout the solid detergent. However, it has now been discovered that by contacting a higher alkylbenzenesulfonate detergent containing oxidizable color bodies with gaseous ozone in the presence of critical proportions of water and total solids, these detergents may be effectively bleached.

The present process is highly effective and economical, and avoids the corrosion experienced when using chlorine-based bleaching agents such as hypochlorites. In addition, residual excess bleaching agent is innocuous and easily removed if desired. Development of objectionable odors such as sometimes follows hypochlorite bleaching, has not been found to occur.

In accordance with the present invention, a process for bleaching a normally solid water-soluble higher alkylbenzene-sulfonate detergent with gaseous ozone comprises admixing a solid water-soluble higher alkylbenzenesulfonate detergent containing oxidizable color bodies with water in an amount sufficient to form an aqueous mixture containing about 40 to 60% water and about 60 to 40% total solids, said detergent comprising at least about 10% of said solids, and intimately contacting said aqueous mixture with gaseous ozone in an amount sufficient to oxidize said oxidizable color bodies and thereby produce said higher alkylbenzenesulfonate detergent in bleached form.

The detergents which are bleached according to the present process are well-known to the art, being normally solid, water-soluble salts of higher alkylbenzenesulfonic acids in which the alkyl group contains from about 10 to 16 carbon atoms, suitable alkyl substituents being exemplified by the decyl, dodecyl, and pentadecyl radicals or mixtures thereof such as may be prepared from polymerized lower olefins, e.g. tetrapropylene and pentapropylene, as well as branched and straight chain substituents prepared from cracked paraffin waxes, kerosene and the like. Preferred detergents are the sodium salt of tetrapropylene- and pentapropylene-benzenesulfonic acids.

Although the preferred salt is the sodium salt, any water-soluble, normally solid salt stable to ozonolysis may be used. Thus, within the ambit of the invention are the alkali metal and alkaline earth salts, i.e. the potassium, lithium, magnesium, and calcium salts; as well as other metallic and non-metallic salts such as the zinc salts and ammonium salts.

The ozone employed may be prepared in the customary manner, e.g. from either air or pure oxygen by means of electric discharge. Because of its lower cost and the proportionately better conversion of oxygen to ozone achieved when using air rather than pure oxygen as an

oxygen source, it is preferred to employ air as a starting material. Typically, the gaseous medium employed for bleaching contains from about 0.25 to 10% or more ozone, and bleaching may be carried out at a temperature within the range of about 15° C. to 70° C. and at any desired pressure (preferably atmospheric) either batch-wise or continuously. In carrying out the present process, the gaseous ozone is dispersed throughout and intimately contacted with a suitable higher alkylbenzenesulfonate-containing aqueous magma or slurry.

The weight ratio of ozone to sulfonate detergent employed is related to the proportion and nature of the oxidizable color bodies associated with the detergent and the ultimate acceptable color, and is best established in any one instance by experiment. However, normally this ratio will vary from about 1:100 to 1:1000.

The ratio of total solids to water employed in the magma or slurry used in carrying out the present process is critical. It has been found that if the level of total solids drops substantially below about 40% by weight (i.e. if more than about 60% by weight of water is present), bleaching efficiency is considerably diminished, and in addition severe foaming, which may cause the bleaching system to flood or overflow, is likely to be encountered. On the other hand, the total solids content of the mixture being bleached must be less than 60% in order to maintain a flowable, pumpable state at ordinary temperatures. A preferred range of total solid contents is from 45% to 50%, the balance being water. The total solids will contain at least about 10% and typically 10% to 95% of higher alkylbenzenesulfonate, the remainder being principally inorganic salts such as sodium sulfate, and oxidizable color bodies. Preferably the total solids will contain from about 40% to about 85% higher alkylbenzenesulfonate.

The following examples are given to additionally illustrate the nature of the present invention and it will be understood that the invention is not limited thereto.

Example I

An aqueous detergent slurry is placed in a closed vessel equipped with an agitator, a thermometer, a gas inlet which extends to the bottom of the vessel, and a gas outlet vent. The slurry contains 50% water and 50% total solids, the solids consisting of about 18% sodium sulfate, about 1% of color bodies and unsulfonated material, and approximately 81% by weight sodium pentadecylbenzene sulfonate.

Air is electrically ozonized and is then passed through the inlet into the slurry, which is agitated. The gas input rate is approximately 10 liters per hour, the gas being at room temperature and at merely sufficient pressure to cause it to flow through the ozonizing and bleaching systems. Each liter of ozonized gas employed contains approximately 30 milligrams of ozone.

During bleaching, only slight foaming occurs, and the temperature of the slurry increases from room temperature to about 40 to 45° C.

The gas outlet vent is connected to a trap containing a solution of potassium iodide which disposes of non-utilized ozone. The trap in turn is vented to the atmosphere through a gas meter. Bleaching is carried out by introducing the ozonized gas into the slurry until it has been treated with 360 milligrams of ozone per 100 grams of sulfonate salt. The unreacted portion of the gas bubbles through the slurry and leaves the vessel by means of the outlet vent. Of the total 360 milligrams of ozone introduced into the slurry, 340 are consumed by the slurry and 20 milligrams are lost in the vented gas. At the end of the bleaching step, the ozonizer is shut off and the ozonizer, bleaching vessel, and remainder of the system is flushed out with a liter of air.

3

The slurry is then removed from the vessel and is roll dried. The Klett color of a 5% aqueous solution of the dried product is 89 as compared to a Klett color of 212 characterizing a 5% aqueous solution of a similarly dried but unbleached portion of the original sulfonate. This also compares favorably with a Klett color of 115 characterizing a sample of the original sulfonate which has been bleached with 1.6 grams of sodium hypochlorite per 100 grams of sulfonate salt.

Example II

The process of Example I is repeated employing a sample of the same batch of sodium pentadecylbenzenesulfonate. The slurry is diluted to a total solids content of 39%, the remainder being water. Oxygen is employed in place of air for ozonolysis, and each liter of the stream of ozonized oxygen contains about 60 milligrams of ozone. Bleaching is carried out using a total of 350 milligrams of ozone per 100 grams of sulfonate salt. A liter of oxygen is used to flush the system after bleaching. Of the 350 milligrams of ozone per 100 grams of sulfonate employed, 320 are consumed by the slurry and 30 are lost in the vented gas. The product, when roll dried and dissolved in water to form a 5% aqueous slurry, is characterized by a Klett color of 111.

Example III

An aqueous slurry containing 53% water and 47% solids is bleached in the manner set forth in Example II. The slurry solids contain 11% sodium sulfate, about 1% of color bodies and unsulfonated organic material, and the remainder is sodium pentadecylbenzenesulfonate. A total of 740 milligrams of ozone per 100 grams of sulfonate are passed through the slurry. After the first 150 milligrams per 100 grams of sulfonate have been passed through the slurry, a noticeable improvement in color occurs. After using 230 milligrams per 100 grams of sulfonate, the sulfonate is quite white in color and thereafter there is little visible improvement as further ozone is admitted. Of the 740 milligrams per 100 grams of sulfonate which are used, 680 are consumed by the slurry and 60 are lost in the vented gas.

The bleached product exhibits a Klett color of 85, which compares with 165 when the original slurry is dried without bleaching and 96 when it is bleached with 1.6 grams of sodium hypochlorite per 100 grams of sulfonate salt.

Specimens of the sodium (or other water soluble) salt of dodecylbenzenesulfonic acid containing oxidizable color bodies may be directly substituted for the sulfonate detergent of Examples I, II and III.

The critical nature of the total solids content of the slurry being bleached may be shown by adding water to the slurry of Example III until it contains 94% water and only 6% total solids. When the bleaching procedure of Example III is applied to this slurry, considerable foaming occurs and even though 1400 milligrams of ozone per 100 grams of sulfonate are used and the slurry consumes all 1400 milligrams, the dried product is characterized by a Klett color of 115.

While there has been disclosed that which is at present considered to be the preferred embodiment of the invention, it will be understood that many changes, modifications or substitutions may be made therein without departing from the true scope of the invention as defined in the appended claims.

What is claimed is:

1. A process for bleaching a normally solid water-soluble higher alkylbenzenesulfonate detergent with gaseous ozone which comprises admixing a solid water-soluble higher alkylbenzenesulfonate detergent in which the alkyl group contains from about 10 to 16 carbon atoms and which detergent contains oxidizable color bodies with water in an amount sufficient to form an aqueous slurry consisting essentially of 40% to 60% water and about 60% to 40% total solids, said total solids containing at least about 10% of said higher alkylbenzenesulfonate detergent, and intimately contacting said aqueous slurry with gaseous ozone in an amount sufficient to oxidize said oxidizable color bodies and thereby produce said higher alkylbenzenesulfonate detergent in bleached form.
2. A process for bleaching a solid water-soluble higher alkylbenzenesulfonate detergent with a gaseous medium containing from about 0.25 to 10% ozone which comprises admixing a solid water-soluble higher alkylbenzenesulfonate detergent in which the alkyl group contains from about 10 to 16 carbon atoms and which detergent contains oxidizable color bodies with water in an amount sufficient to form an aqueous slurry consisting essentially of about 40% to 60% water and about 60% to 40% total solids, said total solids containing at least about 10% of said higher alkylbenzenesulfonate detergent, and intimately contacting said aqueous slurry with an amount of a gaseous medium containing about 0.25 to 10% ozone sufficient to oxidize said oxidizable color bodies and thereby produce said higher alkylbenzenesulfonate detergent in a bleached form.
3. A process for bleaching a sodium salt of a higher alkyl benzenesulfonic acid with gaseous ozone which comprises admixing a normally solid salt of a higher alkylbenzenesulfonic acid in which the alkyl group contains from about 12 to 15 carbon atoms and which detergent contains oxidizable color bodies with water in an amount sufficient to form an aqueous slurry consisting essentially of from about 45 to 50% total solids, the balance being water; said total solids containing about 55 to 60% of said higher alkylbenzenesulfonate, the remainder thereof being principally inorganic salt and oxidizable color bodies; and intimately contacting said aqueous slurry at a temperature of about 15° C. to 70° C. with an amount of a gaseous medium containing from about 1% to 4% ozone sufficient to oxidize said oxidizable color bodies and thereby produce said higher alkylbenzenesulfonate detergent in a bleached form.
